UNITED STATES PATENT OFFICE.

ADELBERT E. BRONSON, JR., OF CLEVELAND, OHIO, ASSIGNOR TO THE BRONSON-WALTON COMPANY, OF SAME PLACE.

DESIGN FOR A COFFEE-MILL SHELL.

SPECIFICATION forming part of Design No. 34,759, dated July 9, 1901.

Application filed June 10, 1901. Serial No. 64,050. Term of patent 14 years.

To all whom it may concern:

Be it known that I, ADELBERT E. BRONSON, Jr., a citizen of the United States, residing at Cleveland, in the county of Cuyahoga and State of Ohio, have invented and produced a new and original Design for a Coffee-Mill Shell, of which the following is a specification, reference being had to the accompanying drawings, forming part thereof.

10 In the drawings, Figure 1 is a front elevation of the shell. Fig. 2 is a rear elevation thereof. Fig. 3 is a side elevation; Fig. 4, a side elevation in central section, and Fig. 5 a plan.

15 As to its leading or material features my design consists of a shell having an approximately circular wall, from the vertical front edge of which extends a dome-like portion having a central hollow boss, while above the 20 dome is a rounded wall connected with the dome and having an open interior communicating with the interior of the dome. Said interior of the dome has grinding-ribs, and at

the outer edge thereof is an annular smooth space.

25 Referring to the parts by letters, A represents the approximately circular wall, which consists of two arcs disconnected above and below. B represents the dome-like portion, connected at its edge with said wall.

30 C represents the hollow boss; D, the rounded wall rising from the dome; E, the ribs on the interior of the dome, and F the annular space at the edge thereof.

G indicates legs supporting the shell.

35 Having described my invention, what I claim is—

The design for a coffee-mill shell, substantially as herein shown and described.

40 In testimony whereof I hereunto affix my signature in the presence of two witnesses.

ADELBERT E. BRONSON, JR.
